UNITED STATES PATENT OFFICE

ROMAINE CLARK CHAPMAN, OF CHESHIRE, CONNECTICUT, ASSIGNOR TO SCOVILL MANUFACTURING COMPANY, OF WATERBURY, CONNECTICUT, A CORPORATION OF CONNECTICUT

DISPLAY CABINET

Application filed February 25, 1928. Serial No. 256,875.

This invention relates to certain improvements in display stands or cases, and has been particularly designed for cases for displaying articles in store windows and the like.

5 It is the especial object of the present invention to provide a display case of strong and rigid construction and of attractive appearance, particularly adapted for holding articles of different sizes in an erect position and other articles in a flat position, the front of the case being provided with viewing apertures through which the articles in the case are visible and may be readily removed for sale.

10 95 A further object of the invention is to provide a display case of novel construction which can be easily and quickly assembled and will offer a wide range for holding articles of different sizes, such as pin packages and safety pins mounted on cards.

15 With these and other objects not specifically referred to in view, the invention consists in certain novel parts, arrangements and combinations which will be described in connection with the accompanying drawings and the novel features pointed out in the claims annexed hereto.

In these drawings, —

20 Figure 1 is a perspective view of the complete case showing the way in which articles may be displayed therein;

25 Figure 2 is a vertical sectional view taken on the line 2—2 of Figure 1;

30 Figure 3 is a similar sectional view taken on the line 3—3 of Figure 1;

35 Figure 4 is a longitudinal sectional view taken on the line 4—4 of Figure 1;

40 Figure 5 is a plan view of a blank from which one part of the case is made;

45 Figure 6 is a plan view of a blank from which the main body of the case is made, and

50 Figure 7 is a plan view of a blank from which another part of the box is made.

Referring now to these drawings, the case and its parts are preferably made of card-board and, as shown in detail, the main portion of the case includes a bottom 1 and a front 2 and a back 3. In Figure 6 the blank from which this part of the case is made is shown. This blank is cut to form the back 3

with side wings 4, 5 and what will be the front portion 2 is cut to form side wings 6, 7, the blank being notched, as indicated at 8, on each side to form the bottom 1. The front portion 2 of the blank is provided with a deep notch 9 terminating in a narrow ledge 10 and, on each side, the deep notch is formed with cutouts 11, 12. The notch 9 and the cutouts 11, 12 form viewing openings. This blank is formed up on the creased lines, indicated at 12' in Figure 6, to form the body, and the wings 4, 5 are then bent on the creased lines 13 inwardly toward the front, and the wings 6, 7 are bent on the creased lines 14 toward the back and overlapping on the wings 4, 5, being secured thereto by paste or in any other suitable way.

On each side of the opening 9 of the front are formed flanges 15, 16 and secured to the inside of these flanges is what may be termed a supplemental front piece, the blank for which is shown in Figure 7. This supplemental front piece includes a body portion or front 17, and the blank is creased at 18 to form end flanges 19. The blank is further creased at 20 to form tabs 21.

In assembling the supplemental front piece and the body, the blank is bent on the creased lines 18 to form the ends 19, these ends acting to space the supplemental front piece rearwardly of the front piece of the main body, and the side tabs 21 are then bent inwardly toward each other and at right angles to the ends 19, and these bent-in tabs are secured by paste or in other suitable manner to the flanges 15, 16 of the main body portion before referred to.

The supplemental front piece 17 is of sufficient width to hold articles laid flatwise, as for instance packages of pins, marked 22 in Figure 1, and the tabs 21 and the flanges 15, 16 of these two parts of the case together with the raised portion 10 of the main front piece of the case act to hold these pin packages in position, but at the same time permit them to be readily removed.

In the best constructions, separate compartments are provided at each end of the case for containing articles, such as safety pin cards 23, which may be viewed through

the openings 11, 12 in the front of the body piece, and preferably for attractiveness in appearance these compartments are shallower than the box. These compartments may be 5 formed in various ways, but in the particular construction illustrated they will be so formed as to stiffen the wings 4, 5, 6 and 7 of the body piece before referred to. A blank for forming one of these compartments is shown 10 in Figure 5. This blank is formed so as to produce, when folded, a square having a front 24 and sides 25, 26 and 27. One of these sides, as side 27, is provided with a tab 28 and the blank is creased, as at 29, so that it can be 15 folded to this shape. The front 24 of this blank is further provided with a viewing opening 30 which registers with the openings 11, 12 in the front of the main body piece. The side 26 may be secured, as by paste, to 20 the wings 4, 5, thus forming a triple thickness of material and consequently a very rigid structure. The tab 28 of the side 27 may be bent to overlap onto the side 25 and the side 25 secured by paste against the back 3 of the 25 body 1. The front 24 may be pasted against the front piece 2 of the main body member and the side 27 may be secured by paste to the end piece 19 of the supplemental front piece 17. Thus a strong, rigid structure is provided. The partition members from the 30 blank shown in Figure 5 are thus secured in each end of the case. Preferably, these are spaced from the bottom of the case so as to cause articles in the partition to project above 35 the case top. This may be done in a simple way by providing stops formed by bending up a piece of cardboard marked 31, as shown in Figure 2, these stops also forming the bottom of the partition members.

40 It will be observed that the supplemental front piece 17 is spaced from the back 3 and this space may be utilized for holding smaller cards of safety pins 32, a block 33 being preferably inserted in the space to elevate the 45 articles carried therein and form the bottom of compartments located in this space. These compartments may be conveniently formed by inserting a center member 35 formed by suitably bending up a piece of cardboard into 50 a square, and this may be secured by paste to the back 3 and supplemental front piece 17, this construction providing three compartments 36, 37 and 38 for holding the smaller pin cards 32.

55 It will be seen with the construction described that a very firm, rigid and attractive display case has been made for such articles as safety pin cards and for the ordinary long pin packages.

60 The case may be covered with paper or other suitable material and may bear any desired indicia, as for instance descriptive matter as to the articles being sold. It will also be understood that the showing of pins as 65 the articles to be displayed is merely illus-

trative and that other articles may be displayed within the invention.

While the case as described is a preferred form, it will be understood that certain changes and variations may be made in the 70 particular construction and arrangement of the parts without departing from the invention as defined in the appended claims.

What is claimed is:

1. A display case or stand comprising a 75 main body piece formed to provide a bottom, front, and back, with wings forming the ends of the case and secured between the front and back, cutouts in the front, a supplemental front piece inset from the main front piece 80 and forming an article holding compartment, narrower article holding compartments at each side of the supplemental front piece, and a compartment between the supplemental front piece and the back of the stand. 85

2. A display case or stand comprising a main body piece formed to provide a bottom, front, and back, with wings forming the ends of the case, cutouts in the front piece, a supplemental front piece inset from the main front piece and having ends, and partition members at each end of the case and engaging the end wings of the case and the ends of the supplemental front piece. 90

3. A display case or stand comprising a 95 main body piece formed to provide a bottom, front, and back, with wings forming the ends of the case and secured between the front and back, cutouts in the front, a supplemental front piece inset from the main front piece and forming an article holding compartment, and article holding compartments at each side of the supplemental front piece, 100 said compartment formed by the supplemental front piece being wider than the side compartments. 105

4. A display case or stand comprising a main body piece formed to provide a bottom, front and back, with wings on the front and back overlapping and forming the ends of the case, cutouts in the front piece, and partition members forming article holding compartments with an article holding compartment between them at each end of the case 110 having cutouts registering with the cutouts in the front piece and secured to one of the wings of the body piece. 115

5. A display case or stand comprising a main body piece formed to provide a bottom, front, and back, with wings forming the ends of the case, cutouts in the front piece, a supplemental front piece inset from the main piece and spaced from the back piece, ends on the supplemental front piece secured to the main front piece, cooperating parts on the front pieces forming guards for retaining articles in place, and an article holding compartment between the front piece and the back. 120

6. A display stand or case comprising a 125

main body piece cut to provide a bottom, front, and back with wings forming the ends of the case, a central front cut-out, side cut-outs on each side of the central cut-out with narrow flanges on adjacent sides of the cut-outs, a supplemental front piece inset from the main piece and opposite the central cut-out, and ends on the supplemental front piece secured to the main front piece, and forming

10 an article holding compartment.

7. A display case or stand comprising a main body piece formed to provide a bottom, front, and back, with wings forming the ends of the case, side cutouts in the front piece, a 15 central cutout in the front piece wider than the side cutouts, flanges on adjacent sides of the central cutout, a supplemental front piece inset from the main body piece and opposite the central cutout, and flanges on the supplemental front piece secured to the main front piece, said supplemental front piece forming an article holding chamber.

In testimony whereof, I have hereunto set my hand.
